ABRAHAM W. LAIR, OF LOS ANGELES, CALIFORNIA.

AUTOMATIC SAFETY VALVE.

Application filed July 24, 1922. Serial No. 577,218.

The object of the invention is to prevent the explosion of a steam boiler by making it impossible to put water in it while under pressure, or at a time when the boiler is dry, or the water is dangerously low. I attain this object by the mechanism illustrated in the accompanying drawings.

It being known that the cause of explosion is that of putting water in an overheated boiler, or at a time when the water is below the flues or tubes, or when the boiler is completely dry, at which time, and in which condition if water is permitted to enter the boiler, coming in contact with the overheated metal, it is converted into the gaseous state with explosive rapidity and explodes the boiler by the rapid liberation of gases.

To prevent the possibility of putting water in the boiler when the water already in it is dangerously low, I have devised an automatic mechanism illustrated in the accompanying drawing which is an elevation partly in section, the mechanism shown consisting of a safety valve A; and an automatic steam float chamber B, by which the valve is operated as shown in the drawing. The steam float chamber is attached to the boiler by means of a pipe 3 passing downward through a hole in the boiler to the low water level. It is securely fastened by a locknut 1 around the pipe.

The steam float chamber connects with the safety valve by means of pipes C, which transmit steam from the boiler through the steam float chamber to the safety valve when the boiler is dangerously dry or when the water is below a safe level within it.

The safety valve is placed in the same position as an ordinary globe valve would be when used to control the steam that operates the boiler feed; (either a pump or an inspirator), a globe valve being used in connection with it is attached to the pipe D, then in case of danger, should the globe valve be opened to start the pump or inspirator—thus causing an explosion—the automatic safety valve will prevent it, because it had already closed through the action of the steam float chamber; and the pump or inspirator cannot be operated; hence, no water can be put into the boiler and consequently there can be no explosion. The pipe 3 connects the steam float chamber to the boiler; D D' represents the pipes that run from the boiler to the pump or inspirator. A globe

valve not shown is connected to pipe D and serves to start or stop the boiler feed.

In operation, when the water in the boiler is at a safe level, the steam pressure in the boiler forces water up through pipe 3 into the steam float chamber B where it raises float 4, thus closing port 5; consequently no steam can pass pipes C to operate the safety valve A, and it then stands open, plug 8 not closing port 14 in the body of the valve, under which circumstance the pump is operated by means of the globe connected to pipe D, as in ordinary circumstances.

When the water in the boiler is dangerously low, the action differs inasmuch that at such times, and under such circumstances, the water leaves the steam float chamber B passing back into the boiler and steam passes up pipe 3 into steam float chamber B, this not being of sufficient specific gravity to buoy up float 4, the latter drops down and rests upon the pegs 23, 24, 25, thus leaving port 5 open, and then steam passes on through pipes C into the cylinder of the safety valve A, where it drives piston 50, piston-head 6, and plug 8 forward, closing port 14 in the body of the valve, under which circumstances and condition the safety valve being closed, the boiler feed, (pump or inspirator) cannot be started.

When chamber B is filled with water, float 4 is buoyed up with a force equal to the weight of the cold water displaced, considering there is no pressure on the boiler. But as the pressure increases the density of the water increases and owing to the increase of density the float will be buoyed up still more, with a force proportional to the density of the water. Hence, the float is buoyed up with a force equal to the weight of cold water displaced, plus the density resulting from the boiler pressure.

Now, given that the mechanism is well assembled and adjusted, when the water in the boiler is of a level sufficient to pass up pipe 3 into chamber B and raise float 4, then port 22 will be closed and no operation of the safety valve 8 is possible. The dropping of float is not entirely instantaneous, for the water in chamber B being hot evolves steam, and as the water level in chamber B lowers by reason of its passage down pipe 3 the space over the water level becomes filled with steam that is evolved from the water

in chamber B and not from the boiler, and this steam escapes through port 5 and fills pipe 41 and the cylinder 12 of valve A, yet not sufficiently strong to operate the piston 6 in said valve, still of sufficient volume to prevent a sudden inrush of steam when the water completely drains from the pipe 3. Following this first release of steam, the float 4 drops completely down, throwing the 10 port 22 wide open, it is then that the entire pressure from the boiler is released and passing port 22 goes to the cylinder 12 and operates the mechanism therein, hence in this action there is no sudden inrush of steam 15 into chamber B. Now as there is no continuous outrush of steam from chamber B, the float 4 merely operates in a volume of confined steam which will not interfere with its action, and on the other hand if there 20 was a continuous outrush of steam as through an opening of pipe 41, then the inrushing steam from the boiler would blow the float 4 upwards.

There is no back pressure from the cylinder 12, for the steam passing through passage 14 is prevented from entering the cylinder when the plug 8 is pushed back into its seat 16, and if perchance a little steam did work through into the cylinder it could 30 not enter the pipe C for it cannot pass the piston 6, the pressure only serving to hold plug 8 all the more secure in its seat 16.

The plug 8 is operated to open passage 14 after an accident has been averted by the 35 closing of passage 14, then the plug 8 is replaced by turning the screw 17 sufficiently to loosen the plug 8, then take off cylinder head 58, reach in and pull back the piston as far as it will come, reinsert cylinder head and turn 40 back screw 17 sufficiently to allow plug 8 to again be driven into its seat across the passage 14, and the mechanism is again ready for another action.

Having thus made a general statement of 45 the object and nature of the invention, with a brief description of the several views of the drawing, the following detailed description of the several parts of the mechanism will cover any omissions occurring in the 50 preceding statements as to construction and materials out of which the invention is made.

The invention consists generally of two main parts known as the body of the valve 55 13, and a cylinder or steam-chest 12 which is permanently attached to the body, both parts being cast together.

14 is the port or opening by which, and through which the steam passes the valve in 60 its circuit from boiler to pump.

8 represents a round metallic plug made of brass or other non-corrosive metal; it is permanently attached to piston 50, and is so constructed that it serves the double purpose of closing port 14 in the body of the 65

valve and also closes the valve seat 16 in the director 11, when 14 is opened. This is accomplished by means of a conical shoulder 9 being turned on plug 8 as shown in the drawing.

50 represents a piston stem, being a permanent part of the plug 8, it carries a piston head 6 which is attached to it by means of a screw 15 which permits of its adjustment anywhere along the piston stem 50.

6 represents a piston head made of brass or other non-corrosive metal.

11 represents a director made of brass or other non-corrosive metal; it is fitted into a socket in the body of the valve by means of 80 screw threads; its function is that of a guide through which the piston slides forward or backward during the operation of the valve. Also within this director a depression 16 is turned which serves the purpose of a valve seat, receiving the conical shoulder 9, of plug 8, when the piston 50 and its attached piston head 6 is moved back so as to leave port 14 in the body of the valve open. Thus, when the valve seat 16 in the director 11 is 90 closed, the steam coming through port 14 is prevented from entering the cylinder portion of the valve.

58 represents the cylinder head used to close the cylinder; it has a nut 10 permanently attached to it by which it can be taken out of the cylinder as occasion requires.

17 represents a screw passing through the body of the valve as shown in the drawing. It is not attached to plug 8, and serves only 100 the purpose of loosening plug 8 in case it becomes wedged into the plug seat through port 14.

In the drawing B represents that part of the invention known as the steam float chamber; it is made up of two half-cylinders 18, 19, of brass or other non-corrosive metal; the two halves being united and held together by screws 20; each half has permanently attached to it a neck 40 which receives the steam pipes 2 and 41.

Within the united half-cylinders the following mechanisms are contained;

4 represents a float; it is made of thin copper or other non-corrosive metal, being merely a thin shell 29; both top, bottom and sides being of the same metal.

24 represents a valve used to close valve-seat 22, when the float is buoyed up by water pressure within the cylinder; it is a part of, and is permanently attached to a carrying rod 45, which passes directly through float 4, being soldered to the metallic shell of the same both above and below.

55 represents a spring made of brass or other non-corrosive metal of sufficient breadth and thickness to insure its perfect holding of float 4 in position within the cylinders; at one end it is attached to the underside of float 4 by means of a screw 26 which en-

ters the lower end of the carrying rod 45, the other end being fastened to the floor of the lower half-cylinder by means of a screw 27, which passes through a small metallic block 28. The object of the spring being that of holding float 4 in central position within the two half cylinders or steam-chest.

21, 31, 23, 32, 25, represent metallic pegs, made of brass or other non-corrosive metal; 10 they are screwed into the floor of the respective halves of the cylinder or steam-chest and are not attached to float 4. Pegs 23, 32, 25, serve the purpose of a rest upon which the float settles when not being buoyed up by 15 water within the cylinders or steam-chest, while 21 and 31, in connection with one not shown in drawing, it being behind the carrying rod 45, serve the purpose of directing valve 24 properly into the seat 22, by preventing float 4 from tilting as the water 20 pressure drives it forward; thus assuring a perfect closing of port 5, in the neck 40 of the cylinder or steam-chest.

49 represents a portion of the neck of the 25 cylinder; it projects downward within the upper half 18 of the cylinder or steam-chest, being permanently cast, and turned within it, the object of which is to provide a suitable mechanism wherein the valve seat 22 is 30 turned.

2 represents a short piece of pipe, connected to pipe 3 by means of a connection 1, all as shown in the drawing.

3 represents a straight pipe which projects 35 downward through the boiler to the low water level; it is attached to the boiler and to the steam trap by means of the connection 1.

1 represents a pipe connector, used to 40 connect the steam trap to the boiler substantially as shown in the drawing.

Having thus described my invention what I claim is:—

1. In an apparatus as disclosed, a valve 45 to be connected in a steam pipe leading from a steam boiler, a cylinder, a piston in said cylinder connected to said valve, a steam pipe leading from the boiler into said cylinder, and means for admitting steam 50 from the boiler into said cylinder to move said piston to close said valve when the water in the boiler recedes to a dangerously low level, and a set screw for engaging said valve to dislodge it from its seat when 55 closed.

2. In an apparatus as disclosed, a steam-operated valve to be connected in a steam pipe leading from a steam boiler, a float chamber, a steam pipe leading from the

boiler to said float chamber, a steam pipe 60 leading from said float chamber to said valve, a float in said float chamber, and a valve controlling said latter steam pipe connected to said float, to be closed by said float when raised by water in said chamber when 65 the water in the boiler is at a safe level, and to be opened by said float when lowered by the discharge of water from said chamber, when the water in the boiler recedes to a dangerously low level, whereby steam is admitted 70 from the boiler through said steam pipes, float chamber and said latter valve to said steam-operated valve to close the latter valve.

3. In an apparatus as disclosed, a steam-operated valve to be connected in a steam pipe leading from a steam boiler, a float chamber, a steam pipe leading from the boiler to said float chamber, a steam pipe 75 leading from said float chamber to said valve, a float in said float chamber, and a valve controlling said latter steam pipe connected to said float, to be closed by said float when raised by water in said chamber when 80 the water in the boiler is at a safe level, and to be opened by said float when lowered by the discharge of water from said chamber, when the water in the boiler recedes to a dangerously low level, whereby steam is admitted 85 from the boiler through said steam pipes, float chamber and said latter valve to said steam-operated valve to close the latter valve, and a spring in said float chamber connected to said float for centering the 90 float and the valve connected thereto. 95

4. In an apparatus as disclosed, a steam-operated valve to be connected in a steam pipe leading from a steam boiler, a float chamber above the boiler, a steam pipe leading from the boiler to said float chamber, a steam pipe 100 leading from said float chamber to said valve, a float in said float chamber, and a valve controlling said latter steam pipe connected to said float, to be closed by said float when raised by water in said 105 chamber when the water in the boiler is at a safe level, and to be opened by said float when lowered by the discharge of water from said chamber, when the water in the boiler recedes to a dangerously low level, whereby steam is admitted 110 from the boiler through said steam pipes, float chamber and said latter valve to said steam-operated valve to close the latter valve, and a spring in said float chamber connected to said float for centering the float and the valve connected thereto. 115

ABRAHAM W. LAIR.
